(57) **CLAIM**

The ornamental design for a composite jewelry stone, as shown and described.

DESCRIPTION

FIG. 1 is a top plan view of an assembled composite jewelry stone of the present invention;

FIG. 2 is a bottom plan view thereof;

FIG. 3 is a right-side elevational view thereof, taken along line 3—3 in FIG. 1, a left-side elevational view being identical; and,

FIG. 4 is a front elevational view, a mirror image of which is a rear elevational view, of the composite jewelry stone shown in FIG. 1.
